OTHER PUBLICATIONS

A sketch of a device used by teachers to create parallel lines on a chalkboard to write musical notes for students. The device had a wooden handle and several metal fingers. Each finger held a piece of chalk. The sketch is based upon a device seen in approximately 1972.

Primary Examiner—Martie Thompson
Attorney, Agent, or Firm—Leydig, Voit & Mayer, Ltd.

[57] CLAIM

The ornamental design for marker holder, as shown and described.

DESCRIPTION

FIG. 1 is a left front top perspective view of the marker holder;

FIG. 2 is a front bottom perspective view thereof;

FIG. 3 is a rear bottom perspective view thereof;

FIG. 4 is a front view thereof;

FIG. 5 is a right side view thereof;

FIG. 6 is a left side view thereof;

FIG. 7 is a rear view thereof;

FIG. 8 is a top plan view thereof;

FIG. 9 is a bottom plan view thereof;

FIG. 10 is a front bottom perspective view thereof with a stamper marker shown in broken lines.

The broken lines showing the stamper marker are for illustrative purposes only and forms no part of the claimed design.
